H. D. PATTERSON,
TRANSLATING DEVICE FOR RAILWAY SIGNALING,
APPLICATION FILED JUNE 1, 1909.

1,121,283.

Patented Dec. 15, 1914.

UNITED STATES PATENT OFFICE.

HAROLD D. PATTERSON, OF MOUNT VERNON, NEW YORK.

TRANSLATING DEVICE FOR RAILWAY SIGNALING.

1,191,938.

Specification of Letters Patent. Patented Dec. 15, 1914.

Application filed June 1, 1909. Serial No. 499,571.

To all whom it may concern:

Be it known that I, HAROLD D. PATTERSON, a citizen of the United States, and a resident of the city of Mount Vernon, county of Westchester, State of New York, have invented certain new and useful Improvements in Translating Devices for Railway Signaling, as set forth in the following specification.

10 This invention relates to signaling systems for electric railways, and more particularly to improved relaying apparatus for use in connection with alternating current systems.

15 In some signaling systems including those described in my prior patent for resonant cab signaling system, patented March 8, 1910, No. 951,546, the controlling current in certain of the circuits varies from a minimum value to a maximum value, whereas, in certain other systems, the signaling current varies from zero to a maximum value. It has been found by the applicant that standard signaling devices which are oper- 20 atively energized by the maximum value of the current but which are inoperatively energized upon the minimum value of the current require a certain degree of delicacy in their adjustment and design which increases 25 their cost although they may operate satisfactorily.

It is an object of this invention to provide for the automatic change of the minimum to maximum variation in the signaling current so that there will result a current varying from zero to maximum which latter current is to be employed for relaying purposes.

It is a further object to do more than 40 merely provide for the creation of a current varying from a zero value to a maximum value, it being contemplated that the creation of a magnetic flux varying from zero to maximum would also be efficient in 45 accomplishing a useful purpose. In fact the invention contemplates means for creating any effective energy manifestation which will vary from approximately zero to a maximum in response to a variation in 50 the signaling current from a minimum to a maximum.

In its broadest aspect the invention contemplates means for transforming an energy variation into a greater percentage en- 55 ergy variation and is well adapted for use

in connection with the Patterson cab signaling systems of the alternating current type, disclosed in my applications and patent:— Se. No. 434,252, filed May 22, 1908; Se. No. 455,179, filed Sep. 28, 1908; Patent No. 60 951,546, granted March 8, 1910.

The above and further objects of the invention will be clear from the following description and will be pointed out more in detail in the accompanying claims which should be read in connection with the accompanying drawings, which form part of this application, in which like characters designate corresponding parts, and in which the figure is a diagram representing the cab installation in its relative relation to the track installation, the latter being shown in vertical section.

1 indicates a source of high constant frequency alternating potential carried on a moving vehicle which is customarily the cab or locomotive.

2 is a suitable primary transformer core suitably suspended beneath the locomotive and having a primary testing winding 3.

4 is a suitable laminated core of magnetic material having windings 5 and 6 wound in opposite directions and which may be of the same number of turns and wound interwoven or sandwiched according to approved transformer construction to prevent magnetic leakage.

7 is a secondary winding of any suitable number of turns which may be in excess of the number in either coil 5 or 6.

8 indicates a suitable translating device, shown as an ordinary alternating current tractive relay.

9 is a solenoid operating the valve 10 for fluid pressure pipe 11.

12 indicates diagrammatically a suitable visible or audible signal; 13 is an adjustable impedance coil suitably proportioned as will hereinafter be explained.

14 is a source of electric energy.

The apparatus described is all carried by the moving vehicle.

Circuits: The circuit for magnetizing primary coil 3 of primary core 2 may be traced as follows:—source 1, wire 15, coil 6, wire 16, coil 3, wire 17, wire 18, back to source 1. The conditions of the current in this normally closed circuit varies according to the magnetic circuit of primary coil 3, which is variable. This circuit is also a variable

magnetizing circuit for core 4 by means of coil 6. This circuit may be termed a signal controlling circuit.

The circuit for opposing coil 5 may be traced as follows:—source 1, wire 15, wire 19, adjustable impedance 13, wire 20, coil 5, wire 21, wire 18, back to source 1. The condition of the current flowing in this circuit may be adjusted by the impedance 13 until the magneto-motive force of coil 5, which opposes the magneto-motive force of the coil 6 has the desired strength relatively to the magneto-motive force of the coil 6 when the minimum current is flowing in the signal circuit into which coil 6 is connected. Then the current through coil 5 of necessity must continue commensurate with the said minimum current flowing in the signal circuit.

The circuit for translating device 8 is as follows:—coil 7, wire 22, translating device 8, wire 23, back to coil 7. This circuit is normally energized, but subject to total de-energization.

The relay circuit shown controlled by translating device 8 may be traced as follows:—source 14, wire 24, circuit closing armature 25, front contact 26, (25 and 26 forming a local circuit controller) to point 27, thence including solenoid 9 and indicating device 12 in parallel, to point 28, thence by wire 29 back to source 14.

In the embodiment illustrated and described in this application, the traffic controlled signaling circuit combined with the present invention is controlled in the manner described in detail in my Patent No. 951,546. For the purposes of this specification it is sufficient to note that a magnetizing current constantly flows from the alternating current generator 1 through the coil 3 to magnetize the core 2, which normally has a large air gap between its poles. Positioned at the track 30, 31, 33 are secondary cores 36 each having a winding 37 and some controlling means 38 for the circuit through the winding 37. The track core 36 is located so as to be interlinked by the magnetic field of the cab core 2 as a train advances along the track thereby to reduce the air gap in the magnetic circuit of the coil 3. When the coil 37 on the track-core 36 is open circuited, the core 36 greatly reduces the reluctance of the magnetic circuit for the coil 3. This causes a reduction in the magnetizing current flowing through the signal circuit and including coil 6. When the coil 37 on the track core is the equivalent of short circuited as by the controller 38, which should be understood to be under traffic control, a dissipation of electric energy in the form of heat is caused. This energy must be supplied by the current in the signal circuit through coil 6 and through coil 3. By this dissipation of energy the reduction in reu-

tance is offset and the current strength is maintained at the normal maximum. Thus it is evident that the current in the signal circuit through coils 6 and 3 varies under traffic control between a maximum value and a minimum value.

The magneto-motive forces of the coils 5 and 6 mounted on the same core 4 are opposed to each other. The magneto-motive force of the coil 3 is made to be substantially equal to the magneto-motive force of the coil 6 when the said minimum current is flowing in the signal circuit including the coil 6. The core 4 subtracts the magneto-motive force of the coil 5 from the magneto-motive force of the coil 6 so that only the excess in magneto-motive force of coil 6 over coil 5 is effective in magnetizing the core 4. The alternating magnetic field set up in core 4 cuts the secondary winding 7 which transforms the alternating magnetic energy into alternating electric energy. As a consequence although the current in the signal circuit varies merely from a minimum value to a maximum value, the magnetic energy in the core 4 varies from zero to a maximum and the electric energy in the coil 7 varies from zero to a maximum. Likewise the relay 8 is either magnetized or de-magnetized. Thus the core 4 may be termed power means oppositely acted upon by the magneto-motive force of the coil 5 and the magneto-motive force of the coil 6 to produce a variation of available energy of a greater percentage variation than the percentage of the current-variation in the signaling circuit including coil 6.

The embodiment and application of the invention as shown is, of course, merely for the purposes of illustration.

To give a better idea of the effect of a change in the percentage of variation of the energy in a signal circuit the following tables are useful:

Table A.

Original variation.....	100 to 90= 10%
Changing subtractor.....	90 to 90
Changed variation.....	10 to 0=100%

It is also appreciated that this transformation may be accomplished in a satisfactory manner for some purposes by using a maximum changing subtractor instead of the minimum, which may be designated concretely as follows:

Table B.

Original variation.....	100 to 90= 10%
Changing subtractor.....	100 to 100
Changed variation.....	0 to -10=100%

It is also to be understood that the invention is not limited to transforming an energy variation into a 100% energy variation but contemplates broadly transform-

ing an energy variation into a greater percentage variation, which may be designated concretely as follows:—

Table C.

Original variation.....	100 to 90-10%
Changing subtractor.....	85 to 55
Changed variation.....	15 to 5-66%

What is claimed and what is desired to be secured by United States Letters Patent is:—

1. In a signaling system, a source of electric energy; a circuit supplied by said source; traffic controlled means for creating a variation of electric energy in said circuit between a maximum value and a minimum value; and electro-magnetic means for changing said variation of energy in said circuit into an energy variation of greater percentage relatively to the maximum value of said last named energy, said means being electrically connected with said circuit.

2. In a railway signaling system, a signal circuit; a source of electric energy for said circuit; traffic controlled means for varying the current condition in said circuit between a maximum and a minimum electrical energy-value in accordance with traffic conditions; and an energy-variation transforming device comprising a magnetizing coil included in said traffic controlled circuit, a second magnetizing coil arranged to be energized by said source to have a magneto-motive force commensurate with the magneto-motive force of said first coil when the current condition in said signal circuit is of said minimum value, and power-means oppositely acted upon by the magneto-motive forces of said magnetizing coils to produce a variation of available energy of greater percentage variation than that of the current-variation in said signal circuit.

3. In a railway signaling system, a signal circuit; a source of electric energy for said circuit; traffic controlled means for varying the current condition in said circuit between a maximum and a minimum electrical energy-value in accordance with traffic conditions; an energy-variation transforming device comprising a magnetizing coil included in said traffic controlled circuit, a second magnetizing coil arranged to be energized by said source to have a magneto-motive force commensurate with the magneto-motive force of said first coil when the current condition in said signal circuit is of said minimum value, and power-means oppositely acted upon by the magneto-motive forces of said magnetizing coils to produce a variation of available energy of greater

percentage variation than that of the current-variation in said signal circuit; and a local circuit controller actuated and operated by said power-means.

4. In an alternating current signaling system, a signal controlling circuit including a source of alternating current and having provisions whereby the current flow in said circuit is normally present but has a variation between a maximum and a minimum value; an electro-magnetic signal device; a transforming device having three coils in interlinked magnetic relation, the first a primary coil included in said signal controlling circuit, the second a secondary coil connected with said electro-magnetic signal device, the third a second primary coil; and means for energizing said second primary coil to give it a constant magnetizing effect equal and opposite to that of said first primary coil when the current flowing in said signal controlling circuit has its minimum value.

5. In an alternating current signaling system, a signal controlling circuit including a source of alternating current and having a traffic controlled device for effecting a current variation in said circuit from a normal maximum value to a minimum value; an electro-magnetic signal device; a transforming device having three coils in interlinked magnetic relation, the first a primary coil included in said signal controlling circuit, the second a secondary coil connected with said electro-magnetic signal device, the third a second primary coil; and means for energizing said second primary coil to give it a constant magnetizing effect equal and opposite to that of said first primary coil when the current flowing in said signal controlling circuit has its minimum value.

6. In an alternating current cab signaling system; a source of constant high frequency alternating potential; a primary testing coil; traffic controlled means for varying the reluctance of the magnetic field of said testing coil; a core having differential windings; a normally closed circuit including said source, said testing coil and one of said differential windings; and a second normally closed circuit including said source and a second of said differential windings.

In witness whereof, I have signed my name to this specification, in the presence of two subscribing witnesses.

HAROLD D. PATTERSON.
